CLAIM

The ornamental design for a simulated linemen American football teaching device, as shown and described.

DESCRIPTION

FIG. 1 is a perspective view of a simulated linemen American football teaching device showing my new design;

FIG. 2 is a top plan view of FIG. 1;

FIG. 3 is a front elevation view of FIG. 1;

FIG. 4 is a rear elevation view of FIG. 1;

FIG. 5 is a bottom plan view of FIG. 1;

FIG. 6 is a right side elevation view of FIG. 1;

FIG. 7 is a left side elevation view of FIG. 1;

FIG. 8 is an enlarged perspective view thereof;

FIG. 9 is a front elevation view of FIG. 8;

FIG. 10 is a rear elevation view of FIG. 8;

FIG. 11 is a top plan view of FIG. 8;

FIG. 12 is a bottom plan view of FIG. 8; and,

FIG. 13 is a side elevation view of FIG. 8, the opposite side being a mirror image thereof.

The broken lines are directed to portions that form no part of the claimed design. The broken line showing of the six additional simulated linemen American football teaching devices are for environmental purposes only and, none of the broken lines form any part of the claimed design.
